UNITED STATES PATENT OFFICE.

WILLIAM L. HUDSON, OF ELLISBURG, NEW YORK.

YIELDING DRIVE MECHANISM.

1,182,486.

Specification of Letters Patent.

Patented May 9, 1916.

Application filed March 3, 1915. Serial No. 11,833.

To all whom it may concern:

Be it known that I, WILLIAM L. HUDSON, a citizen of the United States, and resident of Ellisburg, in the county of Jefferson and State of New York, have invented certain new and useful Improvements in Yielding Drive Mechanism, of which the following is a specification.

This invention relates particularly to a drive mechanism such as is used in motion-picture machines, either those in which a film-strip is exposed, as in a camera, or those in which pictures are projected from a film-strip.

In connection with the take-up reel of a motion-picture machine it is necessary to employ means for rotating the reel constantly, and in order to insure that the rotation shall be sufficient to maintain the film under sufficient tension, while at the same time compensation shall be made for the varying diameter of the roll of film on the reel, it is desirable to employ frictional yielding connections between the reel and the mechanism by which it is rotated.

The object of the present invention is to provide simple and effective frictional connections between these parts and to provide for a convenient adjustment of the degree 30 of friction in these connections, and the invention resides in the novel construction for that purpose hereinafter described.

In the accompanying drawings:—Figure 1 is a side-elevation of a portion of a motion-picture projecting machine embodying the present invention, with parts shown in section; Fig. 2 is a view, on a larger scale, of the adjustable frictional connections between the driving-pulley and the shaft of 40 the take-up reel, shown from the inner side of the pulley; and Fig. 3 is a sectional view on the line 3—3 in Fig. 2.

The invention is illustrated as embodied in a machine in which the film-strip 10 is guided and fed downwardly between two vertical guide-plates 11 and 12, the feeding movement being produced by pivoted feed-dogs 13 which engage the perforations in the margins of the film, in a well-known manner. The feed-dogs are reciprocated by mechanism including a pitman 16 operated by a crank-pin on a disk 17 at the end of a shaft 18 which is geared to the power-shaft 19 of the machine. This power-shaft is 50 provided with a pulley 20 which is connected, by a belt 21, with a pulley 22 con-

nected with the shaft 23 by which the take-up reel 14 is supported and rotated, and accordingly the reel is rotated constantly when the feed-mechanism is in operation. 60

The film, after passing downwardly between the guide-plates 11 and 12, passes beneath a fixed guide or abutment 25 which is cylindrical in form and of a sufficient diameter to prevent the film from being bent 65 to a sharp angle in passing around it. From the guide 25 the film passes, in a reverse direction, to and over a similar fixed guide 26, and from the latter it passes through the wall of the casing 15, between guide-rollers 70 24, and to the reel 14. Since the reel tends to rotate at a constant speed as driven by the belt 21, while the film is delivered intermittently by the feed-mechanism, it will be apparent that at constantly recurring intervals 75 a certain amount of slack film will be present between these instrumentalities. By means of the fixed guides 25 and 26, however, I dispose effectively of this slack film, while at the same time maintaining sufficient 80 tension on the film, as it is wound upon the take-up reel, to cause it to be wound closely. 85

Owing to the resiliency of the film itself it tends, whenever slackened, to assume a smoothly curved form in those parts of it 90 which, as shown in Fig. 1, extend straight between the guide-plates 11 and 12 and the guide 25, and between the latter and the guide 26. Accordingly, at each operation 95 of the feed-mechanism the film which is delivered thereby more rapidly than it can be taken up by the reel is absorbed, so to speak, by this change in the disposition of the film from a straight course to a curved course, and at the same time the slight friction of 100 the film against the guides 25 and 26 is sufficient to cause the slackness from passing freely around the guides and loosening the portion of the film which stretches between the guide 26 and the reel to such an extent 105 as to permit the film which has already been wound from loosening upon the reel.

Since it is necessary, in order to insure close winding of the film, that there be a tendency to drive the reel always somewhat 110 faster than is absolutely necessary to take up the film as delivered by the feed-mechanism, I have so proportioned the gearing and the drive-pulleys as to tend to drive the reel at the maximum speed necessary, and have 115 interposed yielding connections between the drive-pulley 22 and the shaft 23 to accom-

modate the surplus movement of the driving-mechanism as the diameter of the roll increases. These connections are shown in Figs. 2 and 3. The pulley 22 is journaled loosely upon the shaft 23 and held thereon by a collar 27. The rim of the pulley is provided, on the inside, with sockets 28 which receive the ends of two leaf-springs 29 and 30, between which the shaft 23 is 5 clasped, the resiliency of the springs causing them to grip the shaft with a certain amount of friction, so that when the pulley is rotated it tends to rotate the shaft also, but with a degree of force which is insufficient to cause injury to the film or the mechanism when the pulley rotates faster than the reel can be rotated in taking up the film. To provide for adjustment of the frictional connection between the pulley and the shaft, 10 and thereby regulate the tension with which the film is wound, an eccentric 31 is mounted on a stud 32, which passes through the web of the pulley and is provided with a slotted head 33 which may be turned by 15 means of a screw-driver. This eccentric bears against the spring 29, and by turning the eccentric the spring may be forced with more or less pressure against the shaft 23, thus varying the degree of friction by which 20 the pulley and the shaft are coupled together. The eccentric is retained in its adjusted position by the friction between it and the spring.

My invention is not limited to the embodiment thereof hereinbefore described and

illustrated in the accompanying drawings, but it may be embodied in various other forms within the nature of the invention as it is defined in the following claims.

I claim:—

1. The combination, with a drive-shaft, of a pulley mounted on and rotatable with respect to the drive-shaft, and a pair of leaf-springs supported, at their ends, upon the pulley and between which said shaft is 45 frictionally clasped.

2. The combination, with a drive-shaft, of a pulley mounted on and rotatable with respect to the drive-shaft, a pair of leaf-springs supported, at their ends, upon the 50 pulley and between which said shaft is frictionally clasped, and adjustable means for regulating the pressure of one of said springs against the shaft.

3. The combination, with a drive-shaft, of a pulley mounted on and rotatable with respect to the drive-shaft, a pair of leaf-springs supported, at their ends, upon the pulley and between which said shaft is frictionally clasped, and an eccentric carried by 55 the pulley and engaging one of said leaf-springs, the eccentric being rotatable to force said spring with a variable pressure against said shaft.

In testimony whereof, I affix my signature 35 in presence of two witnesses.

WILLIAM L. HUDSON.
